UNITED STATES PATENT OFFICE.

ED CURTIS SMITH, OF GRAHAM, OKLAHOMA.

SUCKER-ROD CATCHER.

Application filed June 1, 1925. Serial No. 34,211.

This invention relates to well apparatus and has particular reference to a catcher for sucker rods and the like.

An important object of the invention is to provide a device of the above character to be mounted in association with a well casing to prevent accidental dropping of the sucker rod within the well casing.

A further object of the invention is to provide a device adapted to limit the downward movement of the sucker rod within the casing.

A still further object of the invention is to provide a device of the above mentioned character whereby the sucker rod may be readily elevated but retained against downward movement beyond a predetermined position.

A still further object of the invention is to provide a device of this character which is extremely simple and durable in construction and designed to operate efficiently.

Other objects and advantages of this invention will become apparent as the description progresses.

In the accompanying drawing forming a part of this specification and in which like numerals are employed to designate corresponding parts throughout the same:

Figure 1 is a side elevation showing the device embodying my invention in association with a sucker rod,

Figure 2 is a similar view showing the device in section,

Figure 3 is a horizontal sectional view taken on the line 3—3 of Figure 2,

Figure 4 is a partial sectional view taken on the line 4—4 of Figure 3, and

Figure 5 is a top plan view of a portion of the device embodying my invention.

In the drawing, wherein for the purpose of illustration is shown the preferred embodiment of my invention, the numeral 10 generally indicates a section of a sucker rod of the type commonly employed in well operations embodying the usual longitudinal body portion 11 of circular cross section and the enlarged extremities 12 of rectangular cross section, one extremity of each section is provided with an internally screw threaded bore and the other extremity with a screw threaded shank as shown at 13 to permit convenient engagement of the adjacent ends of the sections.

As is well known to those familiar with

the art, the sucker rod operated within the well casing is composed of a plurality of sections as indicated at 10. It is often necessary when repairing or replacing parts of the well operating mechanism to withdraw the sucker rod from the casing. This is usually accomplished by elevating the sucker rod and removing the uppermost sections this operation being repeated until all of the sections have been removed from the well. During the removal of the uppermost sections the remaining lower sections extending within the well casing are held in position by suitable mechanism and it frequently happens that this holding mechanism is faulty and improperly secured on the sections permitting the sections in the well to drop to the bottom. This causes great inconvenience and expense in engaging and elevating the lowered sections. With this in mind, I have provided means to prevent the accidental dropping of the sucker rod sections should they become disengaged from the retaining mechanism.

Referring now more particularly to the apparatus embodying my invention, the numeral 14 generally designates a supporting sleeve of cylindrical formation, the inner diameter being great enough to permit convenient passage of the enlarged extremities 10 of the sections 10. The intermediate portions of the outer wall of the sleeve 14 are tapered downwardly to provide walls of heavier construction on the upper extremity, the purpose of which will be hereinafter more fully described. The lower end of the sleeve 14 is externally threaded as at 15 for connection with suitable retaining means mounted adjacent the upper extremity of the well casing. It is to be noted that the sleeve 14 may be constructed of two complementary sections connected by tongue and groove connections or in any desirable manner.

The upper extremity of the sleeve 14 carries a tilting cover 16 of circular construction adapted to snugly fit on the upper edge of the sleeve. This cover is provided with a radially directed slot 17 extending from the central portion of the cover to the outer edge thereof, the purpose of this construction will become apparent as the description progresses. This cover is substantially equal in its outer diameter to the upper wall of the sleeve and is provided on the lower face 110

thereof with an annular flange 18 adapted to snugly fit the interior of the sleeve to provide a durable and well fitting structure.

Secured upon the cover 16 diametrically opposite the slot 17 is an angular bracket lever 19 provided adjacent the edge of the cover with a U-shaped depression 20 engageable with an angular bracket 21 to form a hinge about which the cover 16 may be tilted. The outer free end of the bracket lever 19 is provided with an extension arm 22 bent downwardly in angular relation to the horizontal plane of the cover and adapted to counterbalance the weight of the cover so as to normally retain the same in an angular tilted position, as shown to advantage in Figure 1.

In use, when the sucker rod sections are being withdrawn from the well casing they are permitted to freely pass through the improved catcher apparatus. The longitudinal body portions 11 of the sections are moved through the cover 16 in its angular tilted position, as shown in Figure 1, by reason of the slot 17 which is built sufficiently wider for this purpose. The enlarged extremities 12 formed on the sections are substantially larger in construction than the slot 17 and, therefore, it is necessary that the cover be forced to a substantially vertical position to permit passage of these enlarged connecting extremities of the sections. Thus it is seen that, during movement of the reduced body portions of the sections the cover 16 remains in angular position but, as the enlarged portions of the sections engage the cover they will swing the same upwardly to a vertical position to permit the sections to pass freely through the sleeve. Due to the peculiar construction of the bracket lever 19 the cover is normally held in its tilted position at an angle of approximately 45°, the arm 22 in this instance retaining a substantially vertical position. In the event that the rod lifting apparatus should accidentally release the uppermost section the entire unit of sections within the well casing would be permitted to drop a distance equalling that of the nearest upper connection of the sections, the maximum downward movement being limited to the length of one section. This

will necessarily be the case as the cover 16 being in an angular position will engage the enlarged connecting extremities of the sections, the cover being forced to a downward horizontal position as shown in Figure 2 and securely retaining the sucker rod thereon.

It is clearly apparent that the device will meet with the approval of those interested in the operation of wells of different character due to the very simple and efficient structure of the catcher which may be manufactured at a very reasonable cost and readily positioned in association with the conventional types of well casings.

It is to be understood that the form of my invention herewith shown and described is to be taken as the preferred example of the same, and that various changes as to the shape, size and arrangement of parts may be resorted to without departing from the spirit of the invention or the scope of the subjoined claims.

Having thus described my invention, I claim:

1. A sucker rod catcher comprising a supporting sleeve, a cover hingedly mounted on the upper end of the sleeve having a radially directed slot formed therein, the said slot being arranged to permit movement of the reduced portion of a sucker rod therethrough and prevent passage of the enlarged portions thereof, and an angular lever secured to the cover adapted to normally swing the cover to a raised angular position.

2. A sucker rod catcher including a supporting sleeve, an angular bracket secured adjacent the upper end of the sleeve, a cover formed to engage the upper end of the sleeve and having a slot formed therein arranged to permit slidable movement therethrough of the reduced portion of the sucker rod but prevent passage of the enlarged portion thereof, and an angular lever secured to the cover having a U-shaped depression formed adjacent the cover connection to provide a hinge bracket for the cover and an outward extension adapted to normally swing the cover to an upwardly directed elevated position.

In testimony whereof I affix my signature.
ED CURTIS SMITH.
